Primary Examiner — Holly Baynham(74) *Attorney, Agent, or Firm* — Tillman Wright, PLLC; Chad D. Tillman(57) **CLAIM**

The ornamental design for a tote bag, as shown.

DESCRIPTION

FIG. 1 is a perspective view of the design for a tote bag of the present invention; and,

FIG. 2 is a top view of the tote bag of FIG. 1.

The dot-dashed broken lines immediately adjacent the shaded areas represent the bounds of the claim and all other broken lines showing the bottom portion of the tote bag are for the purposes of illustrating environment. None of the broken lines form a part of the claimed design.

1 Claim, 2 Drawing SheetsFIG. 1

FIG. 2
